UNITED STATES PATENT OFFICE.

DAVID J. WILLIAMS, OF HERRIN, ILLINOIS.

MINING-DRILL BIT AND COUPLING.

1,318,940.

Specification of Letters Patent.

Patented Oct. 14, 1919.

Application filed March 4, 1918. Serial No. 220,333.

To all whom it may concern:

Be it known that I, DAVID J. WILLIAMS, a citizen of the United States, residing at Herrin, in the county of Williamson and State of Illinois, have invented certain new and useful Improvements in Mining-Drill Bits and Couplings; and I do declare the following to be a full, clear, and exact description of the invention, such as will enable others skilled in the art to which it appertains to make and use the same.

My invention has for its principal object to provide an extremely simple and inexpensive, yet a highly efficient and durable bit for mining drills, the construction being such that a single metal plate may be employed in the manufacture of the device.

A further object is to provide simple yet efficient coupling means for attaching the bit to the drill.

With the foregoing general objects in view, the invention resides in the novel construction of the bit hereinafter fully described and claimed, and shown in the accompanying drawing wherein:

Figure 1 is a perspective view of the invention applied to a mining drill stem;

Fig. 2 is a vertical section;

Fig. 3 is a perspective view of the bit and the coupling by which it is attached to the drill stem; and

Fig. 4 is a plan view of the blank from which the bit is constructed.

In the manufacture of the bit, a single substantially rectangular plate 1 is employed, said plate being elongated vertically and having a central rectangular tongue 2 formed integrally with and depending from its lower edge, said edge having a notch 3 at each edge of the tongue. The metal between the notches 3 and the vertical edges of the plate 1 is bent in opposite directions to form a pair of cutting teeth 4.

The lower end of the tongue 2 is provided with a central V-shaped notch 5 and the metal on opposite sides of this notch is bent laterally in the same direction as the teeth 4 to provide additional cutting teeth 6. These teeth form a comparatively small bore 50 and this bore is continuously counterbored by the teeth 4.

The upper end of the plate 1 is formed with a relatively large rectangular notch 7 to receive a coupling 8 by means of which 55 the bit is attached to the ordinary drill stem of helical form D, said plate being provided

immediately below said notch with a bolt hole through which one of the bolts 9 of the coupling 8 passes. The metal on opposite sides of the central notch 7 is bent laterally in the opposite direction from the teeth 4 and 6 to form a pair of ears 10 adapted to elevate the material toward the drill D so that the latter may come into play to remove such material from the bore. 60

The coupling 8 above referred to is in the form of a vertically elongated block having kerfs 11 in its upper and lower ends into which the drill and the drill bit extend, and the notch 7 is of such a width that the ears 10 about opposite sides of the aforesaid block and thus hold the bit against lateral tilting. The coupling 8 is preferably identical in size and shape at both ends for ease of installation. 65

It is to be observed that the kerfs in the upper and lower ends of the coupling block 8 are disposed in planes at right angles to each other and that the ears 10 possess substantially the same inclination as the helix 80 of the drill stem D. By locating the kerfs in the manner shown, the inclined ears are disposed for coaction with the helix of the drill stem in feeding the material from the bore as it is cut by the teeth 4 and 6. If 85 the bit 1 were located in the same plane with the flat end of the drill D, no ears such as 10 could be provided without constructing the bit of much greater width than the drill stem, and this would be undesirable since the 90 drill stem would have a tendency to whip and spring in the comparatively large bore which would be formed by the bit.

From the foregoing, taken in connection with the accompanying drawing, it will be 95 obvious that although my invention is of extremely simple and inexpensive nature, it will be highly efficient and desirable. Since the best results are obtained from the exact construction shown, this construction is 100 preferably employed, but within the scope of the invention as claimed, minor changes might well be made.

I claim:

In combination, a mining drill stem of 105 helical form having a flat end, a substantially flat drill bit having transversely spaced ears on its attaching end, said ears having substantially the same inclination as the helix of the drill stem, a coupling block 110 between said drill stem and bit and having kerfs in its ends disposed in planes at right

angles to each other, one of said kerfs receiving said flat end of the drill stem and the other receiving the part of said bit between said ears, whereby to position said 5 ears for coaction with the drill stem helix, and means for securing said bit and drill stem in said kerfs.

In testimony whereof I have hereunto set my hand in the presence of two subscribing witnesses.

DAVID J. WILLIAMS.
